PIPE NIPPLE AND COUPLING APPLYING AND
REMOVING TOOL

Joseph W. Wilder, Memphis, Tenn.

Original application April 26, 1938, Serial No.
204,425. Divided and this application April 5,
1939, Serial No. 266,191

2 Claims. (Cl. 81—53)

The present application is a division of my co-pending application Serial No. 204,425, filed April 26, 1938.

This application relates to tools for removing and applying pipe nipples, couplings and the like and has for its primary object to provide a tool of this character adapted for engagement with the nipple or coupling for applying or removing the same from inaccessible places.

10 More specifically, the present invention relates to a tool of this character forming a holder for L fittings while applying or removing the same.

Other objects and advantages reside in the details of construction and manner of operation as more fully hereinafter described and claimed, reference being had to the accompanying drawing forming part hereof, wherein like numerals refer to like parts throughout, and in which—

20 Figure 1 is a vertical sectional view showing the holder for the L fitting, and

Figure 2 is a bottom plan view thereof.

Referring now to the drawing in detail, the numeral 30 designates the substantially cylindrical head of the tool having the recess 31 within which the L fitting 29 is positioned. The outer end of the recess is formed with a shoulder 32 upon which one end of the fitting is adapted to rest while a plate 33 bears against the opposite end of the fitting and is held in position by a set screw 34 threaded through the wall of the head. A plate 33 may be provided with a threaded plug 35 for threaded insertion in the end of the L.

35 Projecting from the head is a stem 36 having

a polygonal formation 37 at its extremity to accommodate a wrench for manipulating the head.

From the foregoing it will be apparent that with the L fitting 29 secured in position within the recess 31 of the tool that the fitting may be 5 easily and conveniently applied to and threaded on the end of an inaccessible pipe and the tool will also be adapted for use in removing the fitting therefrom in a manner as will be apparent.

10 It is believed the details of construction and manner of operation of the device will be readily understood from the foregoing without further detailed explanation.

Having thus described the invention, what I 15 claim is—

1. A pipe elbow applying and removing tool comprising a recessed elbow receiving head, a lug adjacent the open end of the recess for supporting one end of the elbow and means carried by a wall of the head for clamping engagement with the other end of the elbow, said means comprising a threaded plug insertable in the said other end of the elbow and a set screw threaded 20 through the wall of the head for engaging said plug.

2. A pipe elbow applying and removing tool comprising a recessed elbow receiving head, a lug adjacent the open end of the recess for supporting one end of the elbow and a clamping screw extending laterally through a wall of the head for engagement with the other end of the elbow.

JOSEPH W. WILDER. 35
